Conrad Harris & Paul W. Goines of Cincinnati, O.
Letters Patent No. 631. Dated Feby. 21st 1854

The schedule referred to in these Letters Patent, and making part of the same
To all whom it may concern:

Be it known that we, Conrad Harris, & Paul W. Goines, both
of Cincinnati, Hamilton County, State of Ohio, have invented a new & useful design, for
Coal Heating Stoves, & we do hereby declare the following to be a full and exact description of
the same, reference being had to the accompanying drawings & letters of reference marked there-
on, to wit: letter A, being a perspective view of the stove, letter B showing the four panels belonging to
forming part of said design, but disengaged & distinct from letter A: What we claim as new, is
Letters Patent, is the combination & arrangement of the ornamental figures, forms & fo-
liage as represented in the annexed drawings, making an ornamental design for
Coal Heating Stoves, known, & called the International
